UNITED STATES PATENT OFFICE.

JOHN S. CLUNE, OF ROSELLE PARK, NEW JERSEY, ASSIGNOR TO THE CONLEY FOIL COMPANY, OF NEW YORK, N. Y., A CORPORATION OF NEW YORK.

ORNAMENTAL PRODUCT AND PACKAGE.

Application filed July 14, 1921. Serial No. 484,737.

To all whom it may concern:

Be it known that I, JOHN S. CLUNE, a citizen of the United States, and resident of Roselle Park, in the county of Union and State of New Jersey, have invented 5 certain new and useful Improvements in Ornamental Products and Packages, of which the following is a specification.

This invention relates to an article of 10 manufacture adapted for use for ornamental or decorative purposes, and relates more particularly to a tinsel or metal foil strip product utilizable, for example, for ornamental displays such as Christmas 15 tree decorations, and has special reference to the provision of such a product put up in packaged form in such manner that the identity or the integrity of the product is maintained and is so available at the time 20 of decorative use.

A prime desideratum of my invention comprehends the packaging of a bundle or group of shredded or strip foil and preferably a variegated or vari-colored bundle 25 of such strip foil in such manner that the individual strips or strands of the bundle be retained in a condition most effective for decorative use. In use for ornamental purposes, it is desirable to have the individual 30 strips or strands in a separable condition to permit freedom of handling of the separated strips as required. Considerable difficulty has been hitherto experienced in this respect. A bundle of the individual 35 tinsel strips, due to improper packaging and marketing, often becomes in the hands of the consumer a mass of interwoven and entangled strands, oftentimes incapable of extrication and separation, in view of the 40 tendency of the strips, especially when cut in very narrow ribbon form, to tear when handled in any but in a tender fashion. I have found that the bundle of foil strips may be so packaged that the identity of the 45 individual strands or strips may be retained during packing and marketing of the product, so that no difficulty will be experienced by the decorator in selecting, separating and handling the individual foil 50 strips. My present invention therefore comprehends the provision of a tinsel or foil strip package in which the identity or integrity of the product is effectively re-

tained, and is so available by the decorator at the time of use.

The principal objects of my invention may be said to include the provision of a novel tinsel or foil product package presenting a variegated scintillating display, the further provision of a package including means for so holding or supporting the tinsel product, preferably in bundle form, 55 that the identity or individuality of the separate strips of the bundle will be maintained by the package during the marketing thereof, and the further provision of a tinsel product package of the nature referred to in which the cost of packaging 60 shall be a negligible quantity, the resulting package presenting the product for sale in 65 a visible and attractive manner.

To the accomplishment of the foregoing and such other objects as may hereinafter appear, my invention consists in the elements and their relation one to the other, 75 as hereinafter particularly described and sought to be defined in the claims, reference being had to the accompanying drawings which show a preferred embodiment of my invention and in which:

Figure 1 is a view showing a plurality of the tinsel strips as put up in bundle form,

Figure 2 is a perspective view of the holder used in the packaging of the bundle,

Figure 3 is a view showing the manner in 85 which the bundle is coiled about the holder,

Figure 4 is a view of a completed package showing the bundle and holder packaged in an envelope adapted therefor, and

Figure 5 is an enlarged view of a portion 90 of one of the preferred tinsel strips.

Referring to the drawings, the tinsel or foil strips to be used for decorative purposes are cut in shredded form from sheets of metal foil, a number of such strips being 95 grouped together as shown at 10 in Figure 1 of the drawings, and preferably tied in the form of a bundle as by means of a ribbon 11. The bundle comprises a plurality of foil strands or strips presenting myriads of specular surfaces providing a scintillating optical effect, the individual strands being adapted to be selected and removed from the bundle and hung in decorative fashion on, for example, the branches of a Christmas tree or 105 other similar object. The decorative dis-

play may be considerably enhanced by utilizing the reflecting properties of the tinsel foil for illuminating a variety of colored surfaces, the composite coloring and illumination being highly pleasing to the eyes of an observer. This result may be accomplished by providing the individual strips themselves with colored surfaces, each strip preferably comprising foil having one of its surfaces colored and the other of its surfaces left clear and uncolored. This is shown, for example, in Figure 5 of the drawings, part of a single strip being shown here in enlarged form. This strip comprises a strand having one of its faces 12 colored, as for example blue, the other of its surfaces 13 being left uncolored. A plurality of such strips having a variety of colors such as the spectrumic colors are grouped together to form the variegated bundle 10. The bundle may be hung with the various strands distributed for display, or the individual strands may be separated, regrouped and suspended in any desired manner. Although I prefer, as shown in the exemplified form herein, to use a variegated bundle of tinsel strips, it will be understood that my invention as hereinbelow described is not limited to the use of such a variegated bundle but includes groupings or bundles of tinsel or strip foil whether colored or uncolored.

It is desired, when the tinsel or strips are required for use, that the individual strips be presented to the decorator in a free and unentangled condition, so that the separated strands may be distributed in the bundle or removed therefrom with facility. Difficulty has hitherto been experienced in this respect, the strands being subject to the liability of becoming interwoven and entangled, the fragile and tearable characteristic of the foil when in fine ribbon form preventing undue handling in disentangling the threads. I have found that the tinsel or strip product may be so packaged that the identity of the individual strips may be retained during packaging and marketing thereof, the individual strips being kept from becoming interwoven and entangled, the strands being capable of separation when desired for decorative use. To this end I provide a holder for the bundle of foil strips, means being preferably provided in the holder for distributively receiving the strands of the bundle and for retaining the same in position and in distributed condition on the holder, the retaining of the strands in their distributed position minimizing or preventing their being interwoven or entangled. Accordingly I provide a holder 14 of the form shown in Figures 2 and 3 of the drawings, the holder being preferably flat and made, for example, of paper board, the bundle

of foil strands being intended to be wound or coiled about the holder, as shown for example in Figure 3 of the drawings. For the purpose of distributively receiving and retaining the strands in position on the holder, the holder is preferably provided with a plurality of toothed or serrated edges 15 and 16, the toothed or serrated edges functioning to effect distribution of the individual strands as the bundle is coiled or wound about the holder, the toothed elements retaining the strands in separated and distributed condition on the said holder. This is illustrated, for example, in Figures 3 and 4 of the drawings, the identity of the tinsel product having been found to be effectively maintained by this manner of packaging the product. Furthermore, by providing a flat holder such as the cardboard holder 14, the foil bundle may be packed in flat form, as illustrated in Figure 3, this presenting a neat, flat resulting package capable of facility of handling during marketing. The provision of a holder having serrated edges further accomplishes the result of preventing the relatively heavy foil strands from gravitating to one side of the holder with the resulting bunching of the strands, the serrated edges thus retaining the strands in distributed fashion, this maintaining the package in perfectly flat condition. For the purpose of preventing any of the end strands from clearing and falling off the holder, the holder is preferably provided with integral enlarged portions, such as 17, acting as stop or retaining means.

To form the completed package, the serrated holder and the strip foil product wound thereon is enclosed in an enveloping means provided therefor, the enveloping means being preferably of a size just sufficient to accommodate the holder, for preventing free play or movement of the holder therein. In order to provide a package in which the tinseled product may be exhibited to the purchasing public without the necessity of removing the product from the package, and for the further purpose of attractively presenting the product for marketing purposes, I prefer to provide a transparent or translucent envelope, such as shown at 18 in Figure 4, the envelope being made, for example, of glacine paper. The evenly distributed variegated foil strips on the holder, when enclosed in the glacine envelope, will be clearly visible through the envelope, the variegated character of the product and the desired even distribution thereof attractively informing the purchaser of the nature and properties of the tinseled commodity, this being illustrated, for example, in Figure 4 of the drawings.

For the purpose of packaging the tinseled product without subjecting the frail strands

of the bundle to liability of breaking and tearing, as is oftentimes the case when the narrow ribbons are subjected to the relatively rough handling incident to rapid packaging methods and for the further purpose of obtaining a resulting package in which the bundle may be removed by the decorator without handling the individual strands in order to minimize tearing of the same, the 10 ribbon securing means 11 is arranged during the coiling of the bundle on the holder so as to overlie a corner of the holder such as, for example, the corner provided by the enlarged stop portion 17, as particularly shown 15 in Figure 3 of the drawings. In the packaging step the ribbon 11 and the end or corner portion 17 are held by the fingers of the operative, the holder being then rotated to effect the coiling of the strands thereon. 20 In this manner the winding of the bundle may be effected with very little handling of the individual strands thereof. The holder and the coiled bundle are then inserted in the envelope 18 with the ribbon 11 located 25 adjacent the opening end of the envelope, with the ribbon ends preferably extending to the outside of such envelope. When desired for use the envelope seal is broken; the ribbon securing means 11 is then grasped 30 by the user or decorator, the user exerting a pull on the ribbon 11 for removing the tinselled product from the container or envelope. As the holder and bundle are removed in this manner, the ribbon 11 only 35 being held by the hands of the user, the holder 14 aided by the weight of the bundle strands lying coiled thereabout will fall from the bundle effecting not only a stripping of the holder from the bundle, but effecting the straightening out of the bundle 40 strands into a condition similar to that shown in Figure 1 of the drawings, the bundle being thus obtained in substantially its original shape, with torn or broken strands 45 reduced to a minimum.

The manufacture and use of the strip foil product and package will, in the main be apparent from the above detailed description thereof. The variegated strips are put up 50 and sold in bundle form, as shown in Figure 1 of the drawings, the bundle being coiled or wound about the flat cardboard backing 14, as shown in Figure 3, the individual strands of the bundle being distributively received and retained in position by the serrated or toothed edges 15 and 16 of the holder. The combined holder and bundle is then packaged and preferably sealed in the 55 glacine envelope, as shown in Figure 4 of the drawings. The cardboard backing not only provides a rigid support for the relatively heavy and frail foil strips, with the further resulting provision of a flat packaged commodity, but the toothed or serrated character 60 of the card provides means for effectively 65

holding the strands in distributed condition, this resulting in providing a perfectly flat package in which the strands are prevented from bunching and in which the strips are further pleasingly distributively displayed 70 not only, but one in which the card holder, when removed from the envelope for use, presents a tinselled bundle capable of removal from the holder with all the strands thereof intact, free and non-entangled. 75

While I have shown my device in the preferred form, it will be obvious that many changes and modifications may be made in the structure disclosed without departing from the spirit of the invention, defined in 80 the following claims.

I claim:

1. As a new article of manufacture, in combination, a holder providing a serrated edge and a bundle of shredded or strip 85 metal foil comprising a plurality of strips or strands of foil coiled about the holder with the strands distributed over the serrated edge and held in position thereby.

2. As a new article of manufacture, in combination, a card holder provided with serrated edges and a bundle of shredded or strip metal foil comprising a plurality of strips or strands of foil coiled about the holder with the strands distributed over the 95 serrated edges and held in position thereby.

3. As a new article of manufacture, in combination, a holder and a bundle of shredded or strip metal foil coiled about the holder; the holder being provided with 100 means for distributively receiving the strands of the bundle coiled thereon.

4. As a new article of manufacture, in combination, a card holder and a bundle of shredded or strip metal foil comprising a 105 plurality of variegated strips or strands of foil, coiled about the holder; the holder being provided with means for distributively receiving the strands of the bundle coiled thereon.

5. As a new article of manufacture, in combination, a holder and a variegated bundle of shredded or strip metal foil coiled about the holder, the holder being provided with means for distributively receiving the 115 strands of the bundle coiled thereon.

6. As a new article of manufacture, in combination, a holder, a bundle of shredded or strip metal foil coiled about the holder; the holder being provided with means for 120 distributively receiving the strands of the bundle coiled thereon and an envelope enclosing the said holder and bundle.

7. As a new article of manufacture, a package comprising a holder providing a 125 serrated edge and a bundle of shredded or strip metal foil wound or coiled about the holder and an envelope enclosing the said holder and bundle.

8. As a new article of manufacture, a 130

package comprising a card holder providing serrated edges and a bundle of shredded or strip metal foil wound or coiled about the holder and an envelope enclosing the said holder and bundle.

9. As a new article of manufacture, in combination, a holder, a bundle of shredded or strip metal foil coiled about the holder, the holder being provided with means for 10 distributively receiving the strands of the bundle coiled thereon and a transparent or translucent envelope enclosing the said holder and bundle.

10. As a new article of manufacture, a package comprising a flat support or holder providing opposed serrated edges, a bundle of shredded or strip metal foil wound or coiled about the holder, the said bundle including a plurality of strips or strands of 15 foil distributed over and held by the serrated edges, the strips being provided with colored and uncolored faces and a glacie envelope of substantially the same size as the support or holder enclosing the holder and 20 the bundle carried thereby.

11. As a new article of manufacture, in combination, a holder and a bundle of shredded or strip metal foil coiled about the holder, the bundle comprising a plurality of 25 strips or strands of foil and a means for securing the strips together, the bundle being

coiled about the holder with the securing means located adjacent an edge of the holder.

12. As a new article of manufacture, in combination, a flat substantially rectangular holder and a bundle of shredded or strip metal foil coiled about the holder, the bundle comprising a plurality of strips or strands of foil and a means for securing 35 the strips together, the bundle being coiled about the holder with the securing means located over a corner of the holder.

13. As a new article of manufacture, in combination, a holder and a bundle of 40 shredded or strip metal foil coiled about the holder, the bundle comprising a plurality of strips or strands of foil, a means for securing 45 the strips together, the bundle being coiled about the holder with the securing means located adjacent an edge of the holder and an envelope enclosing the said holder and bundle with the securing means located adjacent the opening of the envelope and adapted to be grasped by the user to effect 50 withdrawal of the bundle and the stripping 55 of the holder therefrom.

Signed at New York, in the county of New York and State of New York, this 5th day of July, A. D. 1921.

JOHN S. CLUNE.
